[57] CLAIM

The ornamental design for a drill for concrete, as shown and described.

DESCRIPTION

FIG. 1 is a plan view of a drill for concrete in accordance with the present design;

FIG. 2 is a perspective view thereof;

FIG. 3 is a front view thereof;

FIG. 4 is a right side view thereof;

FIG. 5 is an enlarged sectional view taken along line 5—5 of FIG. 3;

FIG. 6 is an enlarged sectional view taken along the line 6—6 of FIG. 3; and,

FIG. 7 is a bottom view thereof.

A rear view is omitted because it is identical to the front view. A left side view is omitted because it is identical to the right side view.
